UNITED STATES PATENT OFFICE.

FRED W. STEIN, OF ATCHISON, KANSAS.

DESIGN FOR A LAUNDRY-RUBBER.

59,939.

Specification for Design.

Patented Dec. 6, 1921.

Application filed December 13, 1920. Serial No. 430,583. Term of patent 7 years.

To all whom it may concern:

Be it known that I, FRED W. STEIN, a citizen of the United States, residing at Atchison, in the county of Atchison and State of Kansas, have invented a new, original, and ornamental Design for a Laundry-Rubber, of which the following is a specification, reference being had to the accompanying drawing, forming part thereof.

Figure 1 is a perspective view of the front of a laundry rubber showing my new design.

Fig. 2 is a perspective view of the back thereof.

I claim:

The ornamental design for a laundry rubber as shown.

FRED W. STEIN.
